(57) **CLAIM**

The ornamental design for a firearm sighting device with attachment point, as shown and described.

DESCRIPTION

FIG. 1 is front view of the firearm sighting device with attachment point;

FIG. 2 is a back view thereof;

FIG. 3 is a right side view thereof;

FIG. 4 is a left side view thereof;

FIG. 5 is a top view thereof;

FIG. 6 is a bottom view thereof; and,

FIG. 7 is a right side view of a firearm with the firearm sighting device with attachment point in place thereon.

The broken lines are for illustration purposes only and form no part of the claimed design.

1 Claim, 7 Drawing Sheets
